O. I. JUDELSHON.
PROTECTOR FOR MECHANISM.
APPLICATION FILED NOV. 9, 1918.

1,301,947.

Patented Apr. 29, 1919.

UNITED STATES PATENT OFFICE.

OSCAR I. JUDELSHON, OF BROOKLYN, NEW YORK.

PROTECTOR FOR MECHANISM.

1,301,947.

Specification of Letters Patent. Patented Apr. 29, 1919.

Application filed November 9, 1918. Serial No. 261,894.

To all whom it may concern:

Be it known that I, OSCAR I. JUDELSHON, a citizen of the United States, and resident of Brooklyn, in the county of Kings and State of New York, have invented certain new and useful Improvements in Protectors for Mechanisms, of which the following is a specification.

The object of my invention is to provide a simple, cheap and effective protector or guard adapted to protect operatives from power driven shafts, motors and the like used for operating machinery.

My invention has particular reference to protectors or guards adapted for use with sewing machine tables and to be interposed between a power driven shaft and motor beneath the table and the operative sitting in front of the table.

20 In carrying out my invention I provide a frame adapted to be secured between the table top and the floor in front of the power driven shaft and driving motor beneath the table top, which frame is provided with a 25 slideable protecting member adapted to be moved to one side to permit access to the driving belt, shaft, etc., said frame also having another protecting member co-operative with the first named member as a permanent 30 shield in front of said shaft or motor.

My invention also comprises novel details of improvement and combinations of parts that will be more fully hereinafter set forth and then pointed out in the claims.

35 Reference is to be had to the accompanying drawings forming a part hereof, in which—

Figure 1 is a perspective view of my improvements in connection with a sewing machine table; Fig. 2 is an end view of Fig. 40 1; Fig. 3 is an enlarged section substantially along the line 3—3 in Fig. 1; and Fig. 4 is an enlarged detail along the line 4—4 in Fig. 3.

45 Similar numerals of reference indicate corresponding parts.

In the accompanying drawings the numeral 1 indicates a sewing machine table shown having a top and legs of any suitable 50 construction, adapted to support a single sewing machine 2, although the table may be of considerable length having mounted thereon any desired number of sewing machines spaced apart in the usual manner.

55 At 3 is indicated a power driven shaft which may be driven by a motor 4, which shaft is

provided with a power driving pulley 5. Said shaft and pulley are adapted for a table for a single sewing machine, as illustrated, or the shaft may extend lengthwise along a 60 table upon which several sewing machines are applied, and pulleys 5 may be upon said shaft for all such sewing machines. A belt 6 extends from the pulley 5 to a suitable transmission mechanism 7, shown supported 65 beneath the table top to receive the belt 8 for operating the sewing machine in the usual manner. A treadle 7^a by means of suitable connections is controlled to operate the transmitting mechanism 7 in a well 70 known manner. Beneath the table top in front of the shaft 3 and the motor, and shown between said shaft and transmission mechanism 7, is an open frame shown comprising spaced upright bars 9 and horizontal bars 10 secured together in a rectangular manner, as by rivets 11. The upper and lower ends of the vertical bars 9 are shown bent laterally at 9^a forming feet which may be secured respectively to the floor 12 and to 75 the under side of the table top by screws for rigidly securing the said frame in place. At 14 is a protecting member or wall mounted upon bars 10 of said frame, and shown in the form of a metal plate having its upper and lower edges 14^a folded to receive said 80 bars, which plate may be secured in a fixed position upon said frame by rivets, which may be the rivets 11 that secure the bars 9 and 10 together. At 15 is a protecting member 85 or wall mounted slidably upon said frame and shown in the form of a metal plate having its upper and lower edges 15^a folded in groove-like form and receiving the upper and lower edges of the member 14 and 90 the horizontal bars 10, whereby one edge portion of member 15 normally rests on the adjacent portion of member 14 to slide thereon and the main portions of the folded parts 15^a receive and can slide along the horizontal bars 10. A handle 16 may be provided 95 upon the member 15 for operating the latter. Upon a bar 10 I preferably provide a stop 17 which may be in the nature of a bolt adjustable in a longitudinal slot 18 in such 100 bar 10, whereby said bolt may be set at a desired position to obstruct movement of member 15 toward belt 6, to retain the adjacent edge of said member out of contact with said belt and yet near the same. The 110 position of the member 15 will be such that it may be slid to one side along the frame

parts 10, 14 with its edge adjacent the belt 6, as shown in Fig. 1, in front of the power shaft and the motor, and may slide along in the other direction to uncover the space between the right hand edge of the member 14 and the belt 6 to permit access to said belt for adjusting it as well as to the motor. When the parts are in the position shown in Fig. 1 the members 14, 15 overlap at adjacent ends and are spread to extend along the bars 10 in a position to provide a complete protector or shield between the operative sitting in front of the table and the power shaft and motor. The lower bar 10 and the members 14, 15 are illustrated at such height as to provide space beneath to permit ready sweeping of the floor below the table.

The frame having bars 9 and 10 and members 14, 15 may be made in suitable dimensions to be individually applied beneath the table whether the latter be adapted for a single sewing machine and operator, or be of extended length for a plurality of machines and operatives.

The protector is simple, cheap in construction, adapted to be readily applied, efficient in use in preventing the clothes of the operative from encountering the drive shaft and motor, and movable member 15, is readily operable to permit access to the drive shaft, motor and the like.

Having thus described my invention, what I claim and desire to secure by Letters Patent is:

1. A protector for mechanism, comprising a frame having spaced horizontal bars and spaced upright bars secured together and adapted to be secured between a table top and a floor, and a protecting member slidably mounted upon said horizontal bars.

2. A protector for mechanism, comprising a frame having spaced horizontal bars and spaced upright bars secured together and adapted to be secured between a table top and a floor, a protecting member secured between said horizontal bars, and another protecting member slidably mounted upon said horizontal bars.

3. A protector for mechanism, comprising a frame having spaced horizontal bars and spaced upright bars secured together and adapted to be secured between a table top and a floor, a protecting member secured between said horizontal bars and another protecting member having its upper and lower edges folded for slidably receiving the first named member and said horizontal bars.

4. A protector for mechanism, comprising a frame having spaced horizontal bars and spaced upright bars secured together and adapted to be secured between a table top and a floor, a protecting member slid-

ably mounted upon said horizontal bars, and a stop upon one of said horizontal bars to limit lateral movement of said slidable member.

5. The combination with a table top for supporting a power driven machine, a drive shaft beneath the table having a pulley, transmitting mechanism supported by the table, a belt extending from said pulley to said mechanism, a frame comprising spaced upright bars and spaced horizontal bars secured to the upright bars, said frame being secured beneath the table between said shaft and said transmitting mechanism, and a protecting wall slidably mounted upon said horizontal bars at one side of said belt.

6. The combination with a table top for supporting a power driven machine, a drive shaft beneath the table having a pulley, transmitting mechanism supported by the table, a belt extending from said pulley to said mechanism, a frame comprising spaced upright bars and spaced horizontal bars secured to the upright bars, said frame being secured beneath the table between said shaft and said transmitting mechanism, a fixed wall secured to said bars and extending part way along said horizontal bars, and a movable wall slidably mounted upon said first named wall and upon said horizontal bars adapted to be moved to a position adjacent said belt.

7. The combination with a table top for supporting a power driven machine, a drive shaft beneath the table having a pulley, transmitting mechanism supported by the table, a belt extending from said pulley to said mechanism, a frame comprising spaced upright bars and spaced horizontal bars secured to the upright bars, said frame being secured beneath the table between said shaft and said transmitting mechanism, a fixed wall secured to said bars and extending part way along said horizontal bars, a movable wall slidably mounted upon said first named wall and upon said horizontal bars adapted to be moved to a position adjacent said belt, one of said horizontal bars having a stop to limit the movement of the movable wall, toward the belt.

8. The combination of a table top for supporting a power driven machine, a horizontal member beneath the table top, means supporting said member spaced above the floor and below the table top, a wall secured between said member and the table top and a wall mounted movably respecting said member and the first named wall.

Signed at New York, in the county of New York and State of New York, this 8th day of November, A. D. 1918.

OSCAR I. JUDELSHON.
